UNITED STATES PATENT OFFICE.

WILLIAM H. GRINDLEY, OF CONGLETON, ENGLAND, ASSIGNOR TO WILLIAM S. PITCAIRN, OF NEW YORK, N. Y.

DESIGN FOR A EWER.

SPECIFICATION forming part of **Design No. 26,789, dated March 23, 1897.**

Application filed December 15, 1896. Serial No. 615,819. Term of patent 3 $\frac{1}{2}$ years.

To all whom it may concern:

Be it known that I, WILLIAM H. GRINDLEY, a citizen of Great Britain, residing at Congleton, in the county of Chester, England, have 5 invented a new and original Design for a Ewer; and I do hereby declare the following to be a full, clear, and exact description of the same, reference being had to the accompanying drawings, forming a part hereof.

10 The principal feature of my design consists in a ewer having an upper and lower body portion resting upon a base portion. The lower body portion is approximately circular in cross-section and is formed of a series of flut- 15 ings alternately large and small proceeding regularly around the ewer. The upper body portion is made up of a similar series of flut- ings in continuation of the flutings of said lower body portion, but of less curvature.

20 The upper outer edge of the ewer is provided with foliate embossed ornamentations simu- 25 lating oak leaves which lose themselves in the body of the dish. Such ornamentations extend downward farther at the front from the lip of the ewer and at the back from the handle portion than from the sides. The base of the ewer, which is bounded outwardly by an irregular curve, is also provided with simi- 30 lar foliate embossed ornamentation which loses itself in the lowermost body portion of the ewer. The handle consists of a scroll terminating in a reverse curve and provided

with knobs or projections and also provided slightly above its center with embossed foliate 35 ornamentations, which gradually lose themselves in the body thereof.

In the drawings which accompany this application and constitute a part thereof, Figure 1 represents a side elevation of the ewer, and Fig. 2 a section of the same made on the 40 plane of the line xx in Fig. 1.

In Figs. 1 and 2, A represents the large flutings, and a the smaller ones in the lower body portion of the ewer.

C represents the flutings in the upper body 45 portion of the same.

O represents the foliate ornamentation along the upper edge of the ewer.

P represents the ornamentation extended down the front thereof, and Q the similar or- 50 namentation at the rear.

S is the ornamentation of the base.

H is the handle, provided with the projec- 55 tions h and the foliate ornamentation R.

What I claim as new is—

The design for a ewer substantially as shown and described.

In testimony whereof I have signed this specification in the presence of two subscr- 55 ibing witnesses.

WILLIAM H. GRINDLEY.
